MINIATURE GOLF GAME COMPRISING RELATIVELY FOLDABLE PLAYING SURFACE ELEMENTS

Anthony Caporuscio, 1120 Webster Ave., Utica, N.Y.

Filed Nov. 26, 1962, Ser. No. 239,954

6 Claims. (Cl. 273—87.2)

This invention relates to a golf game and relates more particularly to a game having a collapsible playing surface adapted to be folded into a compact unit for handling or storage of playing surfaces and clubs and balls.

A primary object of this invention is the provision of a game having all of the excitement of actual golf, but which may be played by a plurality of participants inside a comparatively small room.

Another object of this invention is to provide such a game wherein the elements are so designed that they may be readily folded, one upon the other, due to the difference in elevation of their playing surfaces.

A further object of this invention is the provision of a golf game wherein the players actually drive the ball in a manner similar to ordinary golf.

Another object of the instant invention is to provide such a game wherein a plurality of obstacles are interposed between the tee and the cup.

A still further object of this invention is the provision of a golf game wherein the playing surface and the ball are covered with materials that tend to stick to each other so that when the ball lands it takes a few bounces before stopping, simulating the action of a real golf ball.

Another object of this invention is to provide a golf game wherein the playing surfaces are covered with a pile fabric having a plurality of upstanding loops and the golf ball is covered with a textile material having integral outwardly extending stiff hooks and spines formed of broken loops of filament and adapted to be retained in the pile fabric of the playing surfaces.

Other and further objects reside in the combination of elements, arrangement of parts and features of construction.

Still other objects will in part be obvious and in part be pointed out as the description of the invention proceeds and as shown in the accompanying drawings wherein there are disclosed preferred embodiments of this inventive concept.

In the drawings:

FIGURE 1 is a top plan view of the playing elements for a golf game in accordance with the instant invention;

FIGURE 2 is a side elevational view, with parts broken away for illustrative convenience, of the golf game of FIGURE 1 with the ball and club in position for use;

FIGURE 3 is a transverse cross-sectional view on line 3—3 of FIG. 1;

FIGURE 4 is a transverse cross-sectional view on line 4—4 of FIG. 1;

FIGURE 5 is a transverse cross-sectional view on line 5—5 of FIG. 1; and

FIGURE 6 is a fragmentary longitudinal cross-sectional view on line 6—6 of FIG. 1.

Like reference characters refer to like parts throughout the several views of the drawings.

Referring now to the drawings in detail and more particularly to FIGURE 1, reference numeral 10 indicates generally the game board for the golf game of the instant invention. The board 10 is comprised of basically two elements, a golf course element indicated generally at 12 and a putting green element indicated generally at 14. The golf course element 12 has a base member 16 surrounded on four sides by a guard rail 18 and supported by a plurality of legs 20 having hinges 22 and foldable

2

braces 24 allowing the legs to be nested in a well known manner.

The putting green element 14 is of less width than the golf course element 12 as can be seen clearly in FIGURE 1 and is pivotally secured thereto at one end by a hinge means 26 so that the putting green element 14 may be folded over the golf course element 12 to provide a compact unit for storage, handling or shipping. The putting green element 14 also has a base member 16 and a pair of foldable legs 20.

Overlying each of the base members 16 is a playing surface 28 preferably formed of a pile fabric having upstanding loops 31 for a purpose to be described further hereinafter. A slope or decline 29, seen in FIGURES 2 and 6, connects the playing surfaces 28 of both the golf course element 12 and the putting green element 14.

Adjacent one outer end of the golf course element 12, an "eagle hole" is defined by a cup 30, and adjacent the hinged inner end of the putting green element 14 a "birdie hole" is defined by means of a cup 32. Adjacent the other end of a putting green element 14, a tee 34 is vertically secured in any conventional manner. The tee 34 is preferably formed of a flexible material such as rubber or the like.

The base member 16 of the golf course element 12 is preferably formed of a sheet metal material having a plurality of obstacles pressed therein such as sand traps 36 and water holes 38, which are depressed slightly as shown in FIGURE 6, and mounds or hills 40 which are slightly elevated. These obstacles are not shown in FIGS. 2—5 and are somewhat exaggerated in FIG. 6 for illustrative convenience. It is to be understood that, for example, the mounds 40 are not raised above the playing surface 28 enough to hinder the folding of the putting green element 14 over the top of the golf course element 12.

The obstacles, along with the "out-of-bounds" areas 42, the "roughs" 44 and the "trees" 46, may be colorfully defined in the material forming the playing surface 28. Also defined in this surface is a plurality of transversely extending lines 48 separating the golf course into a plurality of driving areas 75, 100, 125, 150, 175, 200, 225 and 250 indicating the length of the drive made by the player as will be more fully understood when the rules of the game are explained further hereinafter.

The putting green element has similar means defining a plurality of concentric circles 50 surrounding the "birdie hole" 32, one circle being provided for each of the driving areas defined on the playing surface 28 of the golf course element 12. The large outer circle is designated as 51 and includes the entire putting green area. It is to be understood that the "eagle hole" 30 and the "birdie hole" 32 may be simply defined by colored areas on the playing surfaces 28 rather than the cups shown, if desired.

Pads or the like may be secured to the corners of the playing surface 28 of the putting green element 14 as indicating at 52 to keep the rules and score of the game in a convenient location for the participants.

To complete the elements necessary for the golf game of the instant invention, a golf ball 54 and a golf club 56 are provided. The golf ball 54 preferably has a surface covering 55 formed of a textile material having integral outwardly extending stiff hooks and spines formed of broken loops of filament for a purpose to be described further hereinafter.

While it is apparent that the elements described hereinbefore may be of any size or shape and formed of any material it has been found preferable to provide a playing board 10 wherein the golf course element 12 is approximately 4 feet in length and 3 feet in width and wherein the putting green element 14 is slightly less than 4 feet in length and approximately 2½ feet in width.

The playing surfaces 28 are preferably retained approximately 1 foot above the supporting surface 60 by the legs 20 and it is to be understood that any means (diagrammatically shown as blocks 21) may be provided at the base of each leg 20 to allow the same to be vertically adjusted in case the supporting surface 60 is uneven.

The tee 34 extends approximately one inch above the playing surface 28 of the putting green element 14 and the golf ball is preferably $\frac{5}{8}$ inch in diameter. It will be apparent that such a small ball will not require much of a variation in the height of the obstacles such as the sand traps 36, the water holes 38 and the mounds 40 to deflect the same as it rolls over the playing surface of the golf course element 12.

The golf club 56 is preferably approximately 22 inches long and has a face about two inches in length with the angle of a conventional 9 iron.

The driving areas formed on the golf course element 12 between the adjacent lines 48 preferably decrease in width, i.e., longitudinally, from approximately a 10 inch width for the "75" yard area to approximately a 4 inch width for the "250" yard area. As shown in FIG. 1 it is preferred to mark the driving areas as increasing by 25 yard increments from 75 yards to 250 yards, the "eagle hole" 30 being slightly beyond the 250 yard line and in the 250 yard area.

The circles 50 surrounding the "birdie hole" 32 differ by approximately $1\frac{1}{2}$ inches in diameter and, as mentioned hereinbefore, one such circle is provided for each of the driving areas.

While it is to be understood that the structure described hereinbefore may be used in any desired manner as a golf game, a preferred method for playing same will now be set forth. The playing board 10 is first set upon the manner shown in FIG. 1 by extending each of the legs 20 and pivoting the putting green element 14 about the hinge means 26. Each player, in turn, places the ball 54 on the tee 34 and by means of the golf club 56 drives the same with the intention of getting close to, or into the "eagle hole" 30. The particular materials 31 mentioned hereinbefore for the playing surface 28 and the covering 55 on the golf ball 54 will cause the ball to take a few bounces after it hits the playing surface 28 on the golf course element 12 and then to stop. Because of the tendency of the two materials 31, 55 to stick to each other, the action will be much like the true action of real golf balls landing on a fairway.

When each player has taken his turn at driving and it is determined in which of the driving areas, "75" yard to "250" yard, the ball 54 comes to rest, they each then play their second stroke by putting the ball back on the tee 34. Also, on the third, fourth, fifth, etc, strokes the ball is always put back on the tee 34.

There is no actual putting in this game, all of the puts being conceded. On the second stroke the player is required to try and get the ball 54 into the "birdie hole" 32 or within the circle 50 surrounding the "birdie hole" 32 which corresponds to the driving area in which the ball 54 stopped on his first stroke. That is, if a player drives "175" yards on his first stroke he must then endeavor to play his second shot within the circle 50 marked "175."

Once any player is in his allotted circle 50, all of the puts are conceded in accordance with the following rules. If two players land within their designated circle 50 on their second shot, both players are conceded two puts and the hole is "halved," that is the players are considered to have required the same amount of strokes to finish the hole, or "hole out."

In order for a player to "eagle" a hole, that is, hole out in two under par, he must land on or in the "eagle hole" 30 with his first stroke only. In order for a player to "birdie" a hole, that is, hole out in one under

par, he must land on or in the birdie hole 32 and this must be done on the second stroke only.

When a player lands within his allotted circle 50 on his second stroke only he is conceded two puts and is considered to have completed the hole for a par 4.

If no player on his second stroke lands within his allotted circle 50, then all of the circles 50 are considered as one large putting green and on the third stroke the player within the circle 51 and nearest the "birdie hole" 32 is conceded one putt for a par 4 while all the other players are conceded two puts for a bogey 5. If only one of the players is within the outer circle 51 on his third stroke he is conceded two puts to win the hole with a bogey 5.

When all the players are playing their second stroke from a penalized position, that is, within one of the sand traps 36, a water hole 38, the rough 44, a tree 46, or out-of-bounds 42, they play for the large outer circle 51 as though they were playing their third shot and the same rules as for the third stroke hold true.

If only one player lands within his allotted circle 50 on his second stroke he is conceded two puts and holes out with a par 4. Now all the remaining players continue to shoot for the large outer circle 51 until each of the players lands within the same when they are conceded two puts. For each time the player misses the large outer circle 51 he is given an additional stroke.

If all of the players miss the outer circle 51 on the third stroke they must again play for this circle. If on the fourth stroke one player lands within the outer circle 51, he is conceded two puts and wins the hole while the remaining players must continue to play for this circle and are conceded two puts when they eventually fall within the same. But if two or more players land within the large outer circle 51 on the fourth stroke the player nearest the "birdie hole" 32 is conceded one putt and wins the hole with the bogey 5.

It is to be noted that each player must hole out if they are playing "Metal Play" whereas if they are playing "Match Play," as soon as one player wins the hole they move on to the next hole. In the former type of game all of the strokes for 18 consecutive holes are added together for a par of 72 and the player having the least strokes wins. In the latter type of play, the winner is determined by the player who wins most of the holes.

If a player is playing from an unpenalized position and misses his allotted circle 50 on his second stroke whereas a penalized player lands within the outer circle 51 on his second stroke (he now lies three or four strokes depending on his penalty which will be further explained hereinafter), the latter player must remain on the outer circle 51 until the unpenalized player shoots. In this play, if the penalty is one stroke and the unpenalized player lands on the large putting green, that is, within the outer circle 51, on his third stroke, the ball nearest the "birdie hole" 32 is conceded one putt and wins the hole with a par 4. But if the penalty is two strokes and the unpenalized player lands within the outer circle 51 in three strokes then both players are conceded two puts and the unpenalized player wins the hole with a bogey 5.

However, if the penalized player lands within the outer circle 51 with his second stroke, thereby lying three, and the unpenalized players lands within the outer circle 51 with his fourth stroke, both players are conceded two puts when they hole out, the penalized player winning the hole with a bogey 5. If the penalized player lands within the outer circle 51 with his second stroke and now lies 4 because of a two stroke penalty, and the unpenalized player lands on the outer circle 51 with his fourth stroke, then both player are conceded two puts and the hole is halved with a double bogey 6.

Any ball protruding over any hazard or obstacle line shall be declared within that hazard and realize its penalty. Any ball protruding over the upper line 48 in its driving area shall be declared in the next higher driving area.

On the putting green, for a ball to be declared within its allotted circle 50 it must not protrude over the line which indicates the outside extremity of that circle.

The penalties are determined as follows:

If on the first stroke the player's ball lands on the 5 putting green element 14, it is declared out-of-bounds for a two stroke penalty;

If the ball lands on a tree 46 the player receives a one stroke penalty;

If in a sand trap 36, a one stroke penalty;

If the ball lands in a rough 44, a one stroke penalty;

If in a water hole 38, a two stroke penalty; and

If out-of-bounds 42, a two stroke penalty.

It will now be seen that there is herein provided a golf game which accomplishes all of the objects of the instant invention and others including many advantages of great practical utility and commercial importance.

Since many embodiments may be made of this inventive concept and since many modifications may be made in the embodiments hereinbefore shown and described, it is 20 to be understood that all matter herein is to be interpreted as merely illustrative and not in a limiting sense.

I claim:

1. A golf game comprising a reduced scale golf ball, a reduced scale golf club, a miniature oblong putting green element having an elevated playing surface, and a miniature oblong golf course element having a substantially less elevated playing surface than said putting green playing surface, the said elements being in end to end contiguous arrangement,

said golf course element having a guard rail there-
around of a height such that the upper edge is sub-
stantially coplanar with the surface of said putting
green element,

hinge means interconnecting the contiguous inner ends
of the elements to allow said putting green element to
be folded over said golf course element.

short leg means vertically supporting said elements
with their horizontally oriented playing surfaces in
spaced relationship to a general support surface,
a vertically extending tee secured centrally of and ad-
jacent the outer end of said putting green element,
means defining a first cup and a series of concentric
numerically valued circles located centrally of the
inner end of the putting green element, the outermost
circle of the series being adjacent said latter end of
said putting green,

means defining a second cup adjacent the outer end of
said golf course element, the latter cup being substan-
tially aligned with said tee and said first cup,

means defining a plurality of depressed obstacles and
protuberant obstacles in the playing surface of the
golf course element between its inner and outer ends,
lines extending longitudinally of said golf course ele-
ment designating inner limits of longitudinal edge
areas representing "out of bounds" zones and outer
limits of longitudinal edge areas representing "in the
rough" zones at each of the sides of the golf course
element and leaving a central playing area there-
between, the width of said central area in a direc-

tion parallel to an end of the golf course element de-
creasing slightly as the second cup is approached from
the inner end of the golf course element,

a plurality of numerically valued lines extending trans-
versely from side to side of the golf course element,
separating it into a plurality of areas of values iden-
tical with those of said circles on the putting green
element,

and means representing a water hole spaced from and
partially encircling the second cup and extending
substantially across the adjacent end of the golf
course element.

2. A golf game in accordance with claim 1 wherein said
playing surfaces of each element are formed of a pile fab-
ric having a plurality of upstanding loops,

and said golf ball is covered with a textile material
having integral outwardly extending stiff hooks and
spines formed of broken loops of filament and
adapted upon contact to be at least partially retained
in the pile fabric of the playing surfaces,
whereby when the ball lands on such surfaces it takes
a few bounds before stopping, simulating the action
of a real golf ball.

3. A golf game in accordance with claim 1, wherein
25 the width of the oblong putting green element is slightly
less than the width of the oblong golf course element,
whereby when the elements are folded, access to the
golf course element is provided by the spaces be-
tween the elements, which spaces are of sufficient size
30 to receive a ball and a golf club for storage, and the
identity of each element is readily apparent.

4. A golf game in accordance with claim 1 wherein said
supporting legs are hingedly attached legs,
35 and each leg possesses at its base means to allow the
leg to be vertically adjusted.

5. A golf game in accordance with claim 1 wherein a
downwardly directed rail is secured around the periphery
of the putting green element with a top edge substantially
40 at the level of its playing surface and with a bottom edge
therebelow,

and a sloping surface at and across the inner end of the
golf course element extending substantially from the
top of said upper edge of said guard rail to the adja-
cent lower playing surface of the golf course element.

45 6. A golf game in accordance with claim 1 wherein
adjacent numerically valued lines indicate equal incre-
ments in yardage value, but are located progressively
closer together as the second cup is approached in a direc-
tion from the putting green element.
